UNITED STATES PATENT OFFICE

117,339

DESIGN FOR AN AUTOMOBILE GRILLE

Robert Cadwallader, Detroit, Mich.

Application August 20, 1938, Serial No. 79,475

Term of patent 7 years

To all whom it may concern:

Be it known that I, Robert Cadwallader, a citizen of the United States, residing at 17580 Pennington Drive, in the city of Detroit, county of Wayne, and State of Michigan, have invented a new, original, and ornamental Design for Automobile Grilles, of which the following is a specification, reference being had to the accompanying drawing, forming part thereof, in which:

Fig. 1 is a front elevation of an automobile grille showing my new design.

Fig. 2 is a side elevation of the grille shown in Fig. 1.

Fig. 3 is a sectional view taken on line 3—3 of Fig. 1 showing the grille on an enlarged scale.

The dominant features of my new design are illustrated in full lines in the drawing.

I claim:

The ornamental design for an automobile grille, substantially as shown and described.

ROBERT CADWALLADER.
